(57) **CLAIM**

The ornamental design for a portable refuse bag supporting device, as shown and described.

DESCRIPTION

FIG. 1 is a perspective view of the outer surface of a portable refuse bag supporting device in an unassembled configuration;

FIG. 2 is a perspective view of the inner surface of the device in an unassembled configuration;

FIG. 3 is an elevation view of the outer surface of the device in an unassembled configuration;

FIG. 4 is a side elevation view of the right side of the device as oriented in FIG. 3;

FIG. 5 is an elevation view of the inner surface of the device in an unassembled configuration;

FIG. 6 is a side elevation view of the right side of the device as oriented in FIG. 5;

FIG. 7 is a top view of the device as oriented in FIG. 3;

FIG. 8 is a perspective view of the device in a storage configuration;

FIG. 9 is an alternate perspective view of the device in a storage configuration;

FIG. 10 is an elevation view of the device in a storage configuration;

FIG. 11 is top view of the device as oriented in FIG. 10;

FIG. 12 is a rear perspective view of the device in a small-diameter use configuration;

FIG. 13 is a front perspective view of the device in a small-diameter use configuration;

FIG. 14 is a top view of the device in a small-diameter use configuration;

FIG. 15 is a rear perspective view of the device in a large-diameter use configuration;

FIG. 16 is a front perspective view of the device in a large-diameter use configuration; and,

FIG. 17 is a top view of the device in a large-diameter use configuration.

The broken line showing in the figures is included for the purpose of illustrating environment and forms no part of the claimed design.
